FIG. 1 is a front top perspective view of a camera handle for a surgical lighthead showing our new design according to a first embodiment;

FIG. 2 is a front bottom perspective view of the first embodiment;

FIG. 3 is a front elevation view of the first embodiment;

FIG. 4 is a left elevation view of the first embodiment;

FIG. 5 is a right elevation view of the first embodiment;

FIG. 6 is a back elevation view of the first embodiment;

FIG. 7 is a top plan view of the first embodiment;

FIG. 8 is a bottom plan view of the first embodiment;

FIG. 9 is a front top perspective view of a camera handle for a surgical lighthead showing our new design according to a second embodiment;

FIG. 10 is a front bottom perspective view of the second embodiment;

FIG. 11 is a front elevation view of the second embodiment;

FIG. 12 is a left elevation view of the second embodiment;

FIG. 13 is a right elevation view of the second embodiment;

FIG. 14 is a back elevation view of the second embodiment;

FIG. 15 is a top plan view of the second embodiment; and,

FIG. 16 is a bottom plan view of the second embodiment.
